UNITED STATES PATENT OFFICE

116,558

DESIGN FOR A PORTABLE BEACH PAD

Robert L. Ficks, Cincinnati, Ohio, assignor to Ficks-Reed Company, Cincinnati, Ohio, a corporation of Ohio

Application July 30, 1938, Serial No. 78,974

Term of patent 3½ years

To all whom it may concern:

Be it known that I, Robert L. Ficks, a citizen of the United States, residing at Cincinnati, in the county of Hamilton and State of Ohio, have invented a new, original, and ornamental Design for a Portable Beach Pad, of which the following is a specification, reference being had to the accompanying drawing, forming a part thereof.

The characteristic feature of the design resides in the back rest member of the article as shown.

I claim:

The ornamental design for a portable beach pad, substantially as shown and described.

ROBERT L. FICKS.
